Primary Examiner—Catherine R. Oliver

(57) CLAIM

We claim the ornamental design for the "golf accessory," as shown and described.

DESCRIPTION

A Magnetic golf ball marker with a spring steel belt clip holder.

FIG. 1 is a front perspective view of the golf accessory holder showing our new design;

FIG. 2 is a front perspective view with the ball marker removed;

FIG. 3 is a side view;

FIG. 4 is a perspective view of the ball marker; and,

FIG. 5 is an exploded perspective view, with the ball marker shown removed.
